UNITED STATES PATENT OFFICE

KENLY C. BUGG, OF ST. LOUIS, MISSOURI

STRIPING DEVICE

Application filed July 5, 1927. Serial No. 203,392.

This invention relates to devices for forming stripes of paint or other substances.

An object of the invention is to provide a device having a portable frame equipped with a supporting slide for guiding the frame in its movements, and having means for engagement with one or more paint applicators, and means for controlling the passage of the paint through the frame to the applicators.

Another object is to improve generally the construction of the device disclosed in my prior application Serial No. 162,006, filed January 19, 1927.

Other objects will appear from the following description, reference being made to the drawings, in which

Fig. 1 is a side elevation of my improved device.

Fig. 2 is a front elevation.

Fig. 3 is a vertical longitudinal sectional view.

Figs. 4 to 14, inclusive, are views showing different types of paint applicators, Fig. 10 being an end elevation of Fig. 8; and Fig. 13 being an end elevation of Fig. 12.

Fig. 15 is a side elevation of the machine equipped with a container for the material used in forming the stripes.

Fig. 16 is a front elevation of the device shown in Fig. 15.

Fig. 17 is a rear elevation.

As shown in Fig. 1 there are two tanks 1 mounted in a supporting ring 2 and an encircling ring 3. These tanks are designed and arranged to contain paint or other substances and are preferably equipped with removable closures 4 provided with pressure-admitting tubes 5 in order to admit pressure to force the paint or other substance from the tanks through the tubes 6 leading to the stripe-forming mechanism and provided with valves 7 of usual or preferred construction for opening and closing the tubes 6.

The frame of the device comprises a body 8 having an angular passage 9 extending therethrough and a flanged projection 10 adapted to be inserted in the end of either of the tubes 6. The tubes 6 may comprise

sections of rubber or other elastic hose and the flanged extension 10 may be inserted in the end of either tube 6 and the connection thus obtained will be maintained by the contraction of the tube around the flanged extension 10.

A valve 11 is mounted in the frame 8 and is to operate to open and to close the passage 9 so as to regulate the flow of the paint or other substance to the applicator for forming the stripe. This valve has an enlarged circumferential shoulder 12 extending into a spring barrel 13 on the upper end of the frame (Fig. 3).

A spring 14 encircles the valve stem within the barrel 13 having one end pressing against the enlargement 12 and the opposite end abutting against a hollow screw 15 within which the valve stem is freely movable. This screw 15 may be screwed to different positions to increase or reduce the tension of the spring 14, or may be removed to permit removal of the valve.

A lever 16 has a yoke 17 embracing the frame 8 between its arms. The arms of the yoke are mounted on a pivot 18. The extremities of the yoke arms 17 have

screws or pins 19 projecting under the valve stem enlargement 12 so that, by pressing the free end of the lever 16 toward the frame 8, the valve 11 may be moved to open position.

By reference to Fig. 3 it will be observed that the passage 9 is angular. This passage has an angle near its discharge end and the valve 11 is in axial alinement with that part of the passage between the angle and the discharge end. Thus, the valve 11 is movable axially or longitudinally. I have found this construction more satisfactory than other types of valves.

The lower end of the frame 8 is provided with an enlarged threaded hole into which different types of brushes or paint applicators may be inserted. Different forms of such applicators are shown in Figs. 4 to 14, inclusive. The applicators shown in Figs. 4 and 5 each comprises a stem 20 designed and adapted to be screwed into the enlarged threaded hole in the lower end of the frame 8 and having on its lower end a pad or tuft 21 through which the paint or stripe-forming

material is forced and is thereby applied in a stripe upon the surface being treated as the machine is moved along the surface. The applicator shown in Fig. 6 includes a shading pen 22. The applicator of Fig. 7 includes a peripherally grooved roller 23, the groove of which serves to shape the substance. The applicator shown in Figs. 8 and 10 comprises a stem 24, the opening through which terminates in a lateral notch 25 which also shapes the material as it is discharged from the stem. In Fig. 9 is shown an applicator for forming two parallel stripes at the same time. This applicator comprises a threaded part 26 and a pair of arms 27 each having a passage therethrough for conducting material to the brushes 28. The applicator of Fig. 11 comprises two threaded stems 29 having an integral connection 30. Each of the stems 29 has a passage therethrough for discharging material to a brush 31. In Figs. 12 and 13 is shown an applicator comprising a threaded stem 32, the passage through which opens into a transverse notch 33 into which the material is discharged and by which the material is shaped into a proper stripe. The device of Fig. 14 comprises a stem 34, the passage through which discharges the material to an applicator pen 35.

The frame 8 pivotally supports an arm 36 which extends downwardly and at its lower end carries a slide 37. This slide 37 has a stem 38 extending through the arm 36 and provided with a clamping nut 39 whereby the slide may be adjusted in different relationships.

A stem 40 extends from the frame 8 through the arm 36 and a spring 41 is mounted on the stem between the frame 8 and the arm 36. This spring presses the arm 36 in a direction away from the frame, the extent of movement of the arm being limited by a nut 42. By adjusting the nut 42 along the stem 41 the arm 36 may be held in any desired relationship in the frame.

An arm 43 is pivoted to the lower end of the frame 8 and extends to the side opposite from the arm 36. This arm 43 has an arcuate slot 44 through which a stem 45 extends, the same having a clamping nut 46 screwed thereon whereby the arm 43 may be held in different adjustments. A rod 47 is adjustably supported by the outer end of the arm 43 and is provided on its lower end with a terminal 48 of non-abrasive material. This rod 47 may be held in different selected adjustments in connection with the arm 43 by a set screw 49. The rod 47 and the slide 37 constitute supports for the frame as the frame is moved along the surface to be striped so that the applicator will press uniformly against the surface when the machine is operated. Further the parts 47 and 37 constitute guides whereby the applicators may be conveniently used to place stripes on rounded or ogee sur-

faces. An adjustable abutment for the arm 36 comprises a screw 36^a extending through the frame 8 and being capable of adjustment to limit movement of the arm 36 toward the frame 8. Further the arm 36 may be clamped between the abutment 36^a and the nut 42.

The invention as shown in Figs. 15, 16 and 17 is provided with means for supporting the container for the paint or other material to be applied. As there shown, the portable and manually manipulative frame 50 constitutes a support for the container 51. The lower end of the container 51 comprises a discharge nozzle 52 opening through an arm 53 of the frame. The container 51 is preferably of the tin-foil type, so that the material may easily be forced out through the applicator stem 54 into the brush 55. To the parts of the device shown in Figs. 15, 16 and 17 which correspond to like parts shown on sheet 1 of the drawings, the same reference characters are applied.

From the foregoing it is apparent that this invention greatly facilitates and expedites the operation of painting stripes on various surfaces, such as on the bodies of automobiles. The device is of comparatively simple construction and is easily operated and by its use the out-put of each operator is largely increased.

I do not restrict myself in unessential particulars, but what I claim is:—

1. A striping device comprising a frame, a tubular paint applicator, means for removably holding said applicator, in connection with said frame, means for delivering paint to said applicator, a guide for said frame having pivotal connection therewith, a spring yieldingly holding said guide away from said frame and permitting said guide to be moved toward said frame, and an abutment limiting extent of movement of said guide toward said frame.

2. A striping device comprising a frame, a tubular paint applicator in connection with said frame, means for delivering paint through said frame to said applicator, a guide for said frame having pivotal connection therewith for movement toward and away from said frame, and a spring yieldingly holding said guide away from said frame and permitting movement of said guide toward said frame.

3. A striping device comprising a frame, a paint applicator in connection with said frame, means for delivering paint through said frame to said applicator, a guide for said frame having pivotal connection therewith, a stem extending from said frame through said guide, a spring on said stem actuating said guide away from said frame, and an element on said stem limiting extent of movement of said guide from said frame.

4. A striping device comprising a frame, a paint applicator in connection with said

frame, means for delivering paint through said frame to said applicator, a guide for said frame having pivotal connection therewith, a stem extending from said frame through said guide, a spring on said stem actuating said guide away from said frame, an element on said stem limiting extent of movement of said guide from said frame, and means limiting extent of movement of said guide toward said frame.
